UNITED STATES PATENT OFFICE.

ADOLPH SWOBODA, OF CAIRO, ILLINOIS.

EXPANSIBLE BARREL-COVER.

SPECIFICATION forming part of Letters Patent No. 278,670, dated May 29, 1883.

Application filed December 22, 1882. (Model.)

To all whom it may concern:

Be it known that I, ADOLPH SWOBODA, of Cairo, in the county of Alexander, and in the State of Illinois, have invented certain new and useful Improvements in Expansible Barrel-Covers; and I do hereby declare that the following is a full, clear, and exact description thereof, reference being had to the accompanying drawings, making a part of this specification, in which—

Figure 1 is a perspective view of my device separated from a barrel and reduced to its minimum size, and Fig. 2 is a vertical central section of a barrel and of said head when applied thereto.

Letters of like name and kind refer to like parts in each of the figures.

The design of my invention is to enable the contents of a barrel to be covered from the air at any point between its upper and lower ends; and to this end it consists in the construction and combination of parts, substantially as and for the purpose hereinafter shown.

In the annexed drawings, A represents a circular disk, of wood, having such dimensions as to enable it to be readily inserted within the open end of a barrel, B. Secured to and extending upward from the center of said disk is a square tube, C, which is provided with a square axial space that is open at its upper end and receives and contains a correspondingly-shaped block, D, which is loosely fitted therein and has such length as to cause its upper end to project above the upper end of said tube.

Resting upon the upper face of the disk A are four plates, E, which have such size and dimensions as to cause them to fill the space between the edge of said disk and the tube C. Said plates have the same shape and dimensions in plan view and are alternately provided with tongues e or grooves e', by which their ends are caused to engage, as seen in Fig. 1. The length of such engaging ends is sufficient to enable said plates to be moved radially outward until their outer edges conform to the diameter of the largest portion of the barrel B without causing the disengagement of said ends. Each plate E is provided with a radial slot, e", through which a screw, F, is inserted into the disk A. Such screw operating to loosely confine said parts together and as a guide to hold its plate central and to compel motion upon a radial line.

Pivoted within an opening, c, that is provided at each side near the upper end of the tube C is a lever, G, which has the curved form shown in Fig. 2, and has its upper inward-turned end, g, loosely contained within a transverse opening, d, that is formed within the block D, while the lower end of each lever is adapted to loosely engage with the inner edge of one of the plates E. As arranged, the plates E may be moved radially outward by a downward pressure upon the block D, while by an upward movement of the latter said plates will be drawn inward.

In use the head, being contracted until it will pass through the upper end of the barrel, is placed upon the surface of the contents of the same and is then caused to fill the space between the sides of said barrel by means of downward pressure upon the operating-block, after which said parts are locked in position by means of a pin, H, that is passed radially inward into said block through an opening in its inclosing-tube or housing.

The outer edge of each plate is preferably provided with pins x, which engage with the barrel sides and prevent vertical movement of the head.

The various parts of the head may be constructed from any suitable material, although wood is preferably employed for all except the pivotal bearings, guide-pins, and engaging pins.

By means of the hereinbefore-described head articles which would be injured by contact with air may be safely kept in a barrel and portions removed therefrom or additions made thereto, as desired.

Having thus fully set forth the nature and merits of my invention, what I claim as new is—

The hereinbefore-described expansible barrel-head, consisting of the disk A, tube C, block D, engaging-plates E, and levers G, combined and arranged to operate substantially as and for the purpose shown.

In testimony that I claim the foregoing I have hereunto set my hand this 16th day of December, 1882.

ADOLPH SWOBODA.

Witnesses:

L. D. BAYLEY,
H. H. CANDEE.
